PACKAGING MACHINE
Viktoras Bilaiss, 7355 S. Sacramento Blvd.,
Chicago, Ill. 60629
Filed Apr. 30, 1964, Ser. No. 363,761
32 Claims. (Cl. 53—243)

This invention relates generally to packaging machinery, and more particularly to an improved machine for packing books of safety matches into small paper boxes called caddies, the caddies normally holding two rows of books of matches and the books of each row being alternately reversely positioned with respect to each other.

Prior to my invention, the books of matches were for the most part packed into caddies by hand, since no satisfactory machine existed which was not relatively complicated and expensive.

An object of my invention is to provide a simple, inexpensive, and improved packaging machine for packing books of safety matches into containers.

Another object of the invention is to provide a machine for packing books of safety matches into caddies, the caddies to be used being telescoped into one another and stacked in the machine in an inverted position, being fed one at a time in an inverted position from the bottom of the stack for the packing operation, and being inverted into an upright position after the packing operation.

A further object of the invention is to provide a machine for packing books of safety matches into caddies, the caddies to be used being telescoped into one another and stacked in the machine in an inverted position, and the machine including vertically reciprocable gripping means for pulling the bottom caddy downwardly from the stack into a position for receiving upwardly fed books of safety matches, and means for varying the pressure with which the gripping means grip the opposite end portions of the caddy from a relatively high pressure exerted by the gripping means when the caddy is being pulled from the stack to a relatively low pressure exerted by the gripping means when the caddy is in match book receiving position, the relatively low pressure enabling the upwardly fed books of safety matches to readily strip the caddy from the gripping means.

Still another object of the invention is to provide a machine for packing books of safety matches into caddies, the caddies to be used being telescoped into one another and stacked in the machine in an inverted position, and the machine including vertically movable gripping means for pulling the bottom caddy downwardly from the stack into a position for receiving upwardly fed books of safety matches, and means for bending the opposite end portions of the bottom caddy in the stack inwardly for gripping by the gripping means, whereby one and only one caddy at a time is gripped by the gripping means even though the caddies may be telescoped into one another by varying amounts and cocked slightly from each other.

A still further object of the invention is to provide a machine for packing books of safety matches into caddies, the caddies to be used being telescoped into one another and stacked in the machine in an inverted position, and the machine including vertically movable gripping means for pulling the bottom caddy downwardly from the stack into a position for receiving upwardly fed books of safety matches, and clamping means for clamping the stack of

2

caddies to prevent upward movement of the bottom caddy into an improper position for gripping by said gripping means, the clamping means being releasable to release the stack of caddies after the bottom caddy has been pulled downwardly therefrom and allow the stack of caddies to fall so that the next caddy assumes a proper position for gripping by said gripping means.

Other objects and advantages will become apparent when the following description is considered along with the accompanying drawings in which:

FIG. 1 is a plan view of a packaging machine constructed in accordance with my invention, certain portions being omitted or broken away for clarity;

FIG. 2 is an elevational view of the machine of FIG. 1 as viewed from the left in FIG. 1;

FIG. 3 is a sectional view taken generally along the line 3—3 of FIG. 1, the left-hand portion of FIG. 3 showing the carriage in a raised position just short of its extreme upper position and the caddy at the bottom of the stack in the magazine about to be gripped by the grippers, and the right-hand portion of FIG. 3 showing the carriage in a lowered position just short of its extreme lower position and a caddy removed from the stack and gripped by the grippers;

FIG. 4 is an enlarged view of one of the separating fingers of FIG. 3;

FIG. 5 is a fragmentary sectional view taken generally along the line 5—5 of FIG. 1;

FIG. 6 is a fragmentary sectional view taken generally along the line 6—6 of FIG. 2; and

FIG. 7 is an elevational view of a biasing arm for the outer grippers.

A packaging machine constructed in accordance with my invention includes a stationary frame supported on a suitable base (not shown). An inlet trough 20 for receiving rows of books of safety matches from a conveyor (not shown) is secured to a pair of side portions 22 and 23 of the frame. A portion 24 of the frame supports an actuator 26 for a vertically reciprocable table 28 having a pair of guide rods 30 respectively disposed on opposite sides of the actuator 26, each guide rod 30 being vertically reciprocable in a pair of bearings 32 secured to the portion 24 of the frame.

A portion 34 of the frame supports an actuator 36 for a vertically reciprocable carriage 38 having a pair of guide rods 40 respectively disposed on opposite sides of the actuator 36, each guide rod 40 being vertically reciprocable in a pair of bearings 42 secured to the portion 34 of the frame.

A portion 44 of the frame is secured to the side portions 22 and 23 as shown in FIGS. 2 and 5. The portion 44 supports an actuator 46 for a horizontally reciprocable pusher 48 having a pair of guide rods 50 respectively disposed above and on opposite sides of the actuator 46, each guide rod 50 being horizontally reciprocable in the portion 44 of the frame, and the ends of the guide rods 50 opposite the pusher 48 having a cam member 52 mounted thereon. For clarity, in FIG. 1 the portion 44 and the parts it supports are shown spaced outwardly of their true positions.

A portion 54 of the frame supports an actuator 56 for a horizontally reciprocable generally U-shaped pusher 58 the leg portions of which straddle the actuator 56 and support a cam member 60 adjacent their free ends and

above the actuator 56. Beyond the actuator 56, the portion 54 is twisted somewhat as a propeller, as can be seen in the end view thereof shown in FIG. 2.

As will be understood, the actuators 26, 36, 46, and 56 each include a cylinder, a piston, and a piston rod extending through one of the closed ends of the cylinder. The actuators may be hydraulically operated, and controlled by solenoid-operated four-way control valves and limit switches, but preferably they are pneumatically operated, and controlled by pneumatically-operated four-way control valves and bleeder valves. The actuators, four-way control valves, and bleeder valves are readily available as standard equipment and need not be further described herein. The four-way control valves and the pneumatic circuitry per se form no part of the invention and need not be shown.

The frame includes a pair of side portions 62 and 63 supported respectively by the portions 22 and 23. The portion 34 is secured between the side portions 62 and 63. A pair of inwardly projecting support members 64 and 65 are mounted respectively on the side portions 62 and 63 for supporting a stack of inverted caddies. The support members 64 and 65 may be formed integrally respectively with the side portions 62 and 63 if desired. A pair of guide members 66 and 67 are secured respectively to the opposite ends of the side portions 62 and 63 from the portion 34 and cooperate with the portion 34 in guiding the upper end portion of a stack of caddies (not shown) supported on the support members 64 and 65.

A generally arcuately curved sheet member 68 is secured to the top edges of the side portions 22 and 23 on the end portions thereof opposite the inlet trough 20. Cooperating with the sheet member 68 to form a curved chute are three pairs of guide rails 70, 71, and 72 secured to a pair of suitable braces 73. The curved chute thus formed receives inverted caddies filled with books of safety matches from the table 28 in the raised position thereof and delivers them upright to the frame portion 54 where for a purpose to be later described they strike a trip member 74 (FIGS. 2 and 6) rigidly secured to a shaft 75 pivotally mounted adjacent opposite ends in a pair of bearings 76 supported on the frame portion 54.

The carriage 38 includes a back portion 38a connected to the actuator 36 and guide rods 40, a pair of side portions 38b and 38c extending parallel to and spaced outwardly respectively from the frame side portions 62 and 63, and a pair of front portions 38d and 38e extending inwardly respectively toward the side portions 62 and 63 from the opposite ends of the side portions 38b and 38c from the back portion 38a.

A pair of shafts 78 and 79 are supported in the carriage 38 respectively between and parallel to carriage portion 38b and frame portion 62 and between and parallel to frame portion 63 and carriage portion 38c. The shafts are supported adjacent one end respectively in the carriage portions 38d and 38e and adjacent the other end in the carriage portion 38a. A plurality of collars 80 are secured to each of the shafts 78 and 79 to maintain proper spacing of other parts mounted thereon and described hereinafter.

Each of the shafts 79 and 80 has an inner gripper 82 and a pair of outer grippers 84 pivotally mounted thereon and cooperable with each other to grip an end of a caddy. Each inner gripper 82 includes a pair of spaced depending arm portions 82a pivotally mounted adjacent one end on their respective shaft and having a pair of integral inwardly extending support portions 82b respectively adjacent their free ends. The inner end portions of the support portions 82b of each inner gripper 82 are connected by a gripper plate 82c secured thereto in any suitable manner.

Each outer gripper 84 is mounted generally centrally thereof so as to include an upwardly extending arm portion 84a and a downwardly extending arm portion 84b. Each arm portion 84a is recessed to receive a compression

spring 85 for a purpose hereinafter described. Each arm portion 84b has an integral inwardly extending support portion 84c adjacent its free end, and the inner end portion of each support portion 84c is provided with a gripper tooth 84d formed integrally therewith and cooperable with the respective gripper plate 82c mounted on the same shaft to grip an end of a caddy.

Each of the carriage portions 38b and 38c has secured thereto a pair of depending spring support housings 86 in alignment with the respective arm portions 82a of inner grippers 82. Each housing 86 contains a compression spring 87 having an end portion anchored to its respective arm portion 82a in any suitable manner. For example, each spring 87 may surround a pin (not shown) mounted on the respective arm portion 82a. The arm portions 82a and therefore the gripper plates 82c are biased inwardly by the springs 87.

One of the problems which has been solved by the packaging machine of my invention relates to the pressure with which the gripper teeth 84d and gripper plates 82c grip the ends of a caddy. The gripping pressure must be sufficiently high to hold a caddy tightly as the carriage 38 is lowered in order that a caddy may be pulled loose from the stack of inverted caddies, and yet the gripping pressure must be low enough to enable a caddy to be stripped from the grippers as the books of safety matches are raised thereinto by the table 28. I have discovered that no single value of gripping pressure fulfills both of these requirements, and therefore I have provided means by which the gripping pressure is varied and which I will now describe.

Each of the shafts 78 and 79 is provided with an upwardly extending biasing arm 90 pivotally mounted between the respective pair of outer grippers 84 and best shown in FIG. 7. Each arm 90 includes a pair of transversely extending portions 91 respectively having a pair of outwardly facing recesses 92 therein aligned with the respective springs 85 for receiving end portions of the respective springs 85 contained in the arm portions 84a of the outer grippers 84. Each arm 90 also carries a roller-type cam follower 93 rotatably mounted on a pin 94.

Each of the frame side portions 62 and 63 has a cam 95 mounted thereon for engagement by the respective cam follower 93. When the carriage 38 is at the top of its stroke, the cam followers 93 will be engaged with the thicker portions of the cams 95 and the springs 85 will exert maximum pressure on the arm portions 84a to force the gripper teeth 84d against the gripper plates 82c with maximum pressure for pulling a caddy from the stack. When the carriage 38 is at the bottom of its stroke, the cam followers 93 will be engaged with the thinner portions of the cams 95 and the springs 85 will exert maximum pressure on the arm portions 84a to force the gripper teeth 84d against the gripper plates 82c with minimum pressure to enable a caddy to be readily stripped from the grippers.

Another problem which has been solved by the packaging machine of my invention relates to the gripping of one and only one caddy at a time when they overlap or are telescoped into each other by varying amounts, such as when one caddy is cocked relative to another and the amount of overlap varies at opposite ends of the caddies. To solve this problem, I have provided means for bending the opposite end portions of the caddy at the bottom of the stack inwardly and away from the end portions of the caddy immediately above or second from the bottom of the stack, so that the grippers may readily grip the end portions only of the caddy at the bottom of the stack. Thus, each of the frame side portions 62 and 63 has a pair of arms 96 pivotally mounted thereon adjacent their upper ends and disposed respectively between the arm portions 82a of the inner gripper 82 and the arm portions 84b of the outer grippers 84. Each arm 96 is provided on one side with a pin 97 which acts as a cam follower and is biased outwardly against an inner surface of a respective arm portion 82a by a compression spring 98 contained within the arm 96 and seated

at one end against one of the frame side portions 62 and 63. Each arm 96 is also provided with a finger 99 pivotally mounted adjacent the lower end of the arm on a pin 100 as best shown in FIG. 4 and biased upwardly into engagement with an end portion of the bottom caddy in the stack by a tension spring 102 secured at one end to the arm 96 and at the other end to the finger 99. As the arms 96 are pivoted outwardly, surfaces 103 of the fingers 99 will engage the edge of an end portion of the bottom caddy, and as the arms 96 are pivoted back inwardly, surfaces 104 of the fingers 99 will bend the respective end portion of the bottom caddy inwardly, as shown at the left side of FIG. 3, so that it may be readily and separately gripped by the respective gripper plate 82c and gripper teeth 84d.

Each of the arm portions 82a of the inner grippers 82 is provided with a cam follower 106 for cooperation with a respective cam 108, as best shown at the right in FIG. 3, two of the cams 108 being secured to each of the frame side portions 62 and 63. The springs 87 maintain the cam followers 106 in engagement with the respective cams 108.

A pair of flat elongated cam plates 110 are pivotally mounted respectively on the frame side portions 62 and 63 between the respective pairs of arm portions 84b to effect movement of the outer grippers 84 with respect to the inner gripper 82, each arm portion 84b being provided with a pin 112 which acts as a cam follower in cooperation with one of the cam plates. Each cam plate 110 is secured adjacent its upper end centrally thereof to an arm 113 which is pivotally mounted on one of the side portions 62 and 63, the arms 113 being narrower than the cam plates to allow the followers 112 to pass over the upper edges of the respective cam plates without interference with the arms 113. Further, each cam plate is provided adjacent its lower end with an opposed pair of slots 114 to allow the respective followers 112 to pass through the cam plate adjacent its lower end. The lower end portion of each cam plate is centrally apertured to receive a screw 116 (FIG. 3), a pair of the screws 116 being threaded respectively into the frame side portions 22 and 23. Each screw 116 has a sleeve or spacer 117 and a compression spring 118 mounted thereon, the spring 118 normally biasing the lower end portion of the respective cam plate 110 against the respective spacer 117 as shown at the left in FIG. 3.

When the carriage 38 is lowered, the cams 108 force the inner grippers 82 outwardly, which in turn force the outer grippers 84 outwardly. At the same time, the followers 112 on the arm portions 84b force the cam plates 110 outwardly (FIG. 3, right). When the followers 112 reach the slots 114 as the carriage 38 completes its downward stroke, the cam plates 110 are snapped by the springs 118 against the spacers 117 and past the followers 112 to locate the cam plates inwardly of the followers 112. When the carriage 38 undergoes its upward stroke, the cams 108 allow the inner grippers 82 to pivot inwardly under the influence of the springs 87, but the cam plates 110 and followers 112 maintain the outer grippers 84 in their outer positions (FIG. 3, left). The gripper teeth 84d thus become separated from the gripper plates 82c so that the end portions of the bottom caddy, as located by the surfaces 104 on the fingers 99, may be respectively received therebetween. When the carriage 38 completes its upward stroke, the followers 112 clear the upper edges of the cam plates 110 and allow the outer grippers 84 to be snapped inwardly under the influence of the springs 85 to clamp the end portions of the bottom caddy respectively between the gripper teeth 84d and the gripper plates 82c.

When the carriage 38 is in its lower position and the grippers 82 and 84 are holding a caddy in position to receive books of safety matches, the table 28 is raised to push the books of safety matches into the caddy and to strip the caddy from the grippers. Should one end of the caddy be released before the other, the caddy might tilt

and books of matches might be spilled. For this reason, a pair of one-way stop members 120 are pivotally mounted respectively on the lower portions of the caddy support members 64 and 65, the stop member on the support member 64 being omitted in FIG. 3 for clarity. The stop members 120 are biased by torsion springs (not shown) to a position in which they prevent excessive upward movement of a caddy upon its being stripped from the grippers, but upon downward movement of a caddy, the stop members 120 are pivoted out of the way by the caddy.

When the stack of caddies becomes relatively small as they are used, their weight acting to hold the bottom caddy against the fingers 99 also becomes relatively small, and the bottom caddy might possibly rise so that its end portions become disengaged from the surfaces 104 on the fingers and resume their original shape so as not to be in proper position for gripping by the grippers 82 and 84. To prevent such an occurrence, a vertically disposed clamping bar 122 is provided to clamp the lower end of the stack of caddies against the frame portion 34 and prevent their upward movement. The clamping pressure must be released, however, to allow the remaining caddies to fall down after the bottom one has been removed by the grippers. Therefore, a cam 124 is provided on the carriage side portion 38c adjacent the front portion 38e. The clamping bar 122 is rigidly mounted on the free end portion of an arm 125 keyed adjacent its other end to the lower end of a shaft 126 rotatably supported in a bearing 128 secured to the guide member 67. An arm 129 is keyed adjacent one end to the upper end of the shaft 126 and carries a cam follower 130 on its free end for cooperation with the cam 124. As the carriage 38 is raised, the cam 124 pushes the follower 130 outwardly to pivot the arm 129, shaft 126, and arm 125, and press the clamping bar 122 against the stack of caddies to maintain the bottom caddy in proper position for gripping. As the carriage 38 is lowered, the bottom caddy is removed from the stack and the cam 124 releases the clamping pressure and allows the remaining caddies in the stack to fall against the support members 64 and 65.

When the table 28 is raised to push two rows of books of safety matches into a caddy, it is possible that some of the books of matches may be out of alignment. To insure that the books of matches are properly aligned before they reach a caddy, a pair of centering vanes 132 (FIGS. 1 and 5) is provided. The centering vanes 132 are rigidly mounted respectively on a pair of shafts 133 rotatably supported adjacent opposite ends in the frame side portions 22 and 23. The centering vanes are normally maintained respectively in proper position by a pair of biasing springs (not shown) which bias a pair of dogs 134 (FIG. 2) respectively secured to the outer end portions of shafts 133 toward engagement respectively with a pair of stops 136 secured to the frame side portion 22.

A number of bleeder valves are provided to control the operation of the machine. Thus, a bleeder valve 140 (FIG. 5) is secured to the frame side portion 23 and is operable by a dog 141 rigidly secured to a shaft 142 rotatably mounted adjacent opposite ends in the frame side portions 22 and 23. A trip member 144 is rigidly secured to the shaft 142 for operation by a row of books of safety matches fed to the table 28 from the inlet trough 20.

65 A bleeder valve 146 is secured to the frame portion 24 for operation by the table 28. A bleeder valve 148 (FIGS. 2 and 6) is secured to a bracket 149 supported by the frame portion 54 and is operable by a dog 150 keyed to the shaft 75.

70 A bleeder valve 152 (FIG. 1) is secured to a bracket 153 supported by the frame portion 44 and is operable by the cam member 52. For clarity, the bleeder valve 152 and bracket 153 are omitted in FIG. 2. A bleeder valve 154 (FIGS. 1, 2, and 6) is secured to a bracket

155 supported by the frame portion 24 and is operable by the cam member 60.

Operation

Assuming that a caddy has been pulled down from the stack by the grippers 82 and 84 into a position for receiving books of safety matches and that rows of books of safety matches are being fed into the machine from the inlet trough 20, when two rows of books of safety matches are on the table 28 and are forced far enough to the right as viewed in FIG. 5, the trip member 144 is operated to turn the shaft 142 counterclockwise as viewed in FIG. 5. The dog 141 is thus pivoted to operate the bleeder valve 140. Operation of the bleeder valve 140 causes shifting of a four-way control valve (not shown) for the actuator 26, and the actuator 26 raises the table 28 to push the two rows of books of safety matches through the centering vanes 132 and into the inverted caddy held by the grippers 82 and 84. It will be noted that raising of the table 28 also cuts off the flow of books of safety matches from the inlet trough 20. Further upward movement of the table 28 strips the inverted caddy containing the books of safety matches from the grippers, the stop members 120 preventing the caddy from rising so high as to spill the books of safety matches, and a portion of the table 28 operates the bleeder valve 146 to shift a four-way control valve (not shown) for the actuator 46. The pusher 48 is then actuated by the actuator 46 to push the inverted caddy containing the books of safety matches off the raised table 28 down the curved chute formed by the curved sheet member 68 and the guide rails 70, 71, and 72.

As the inverted caddy is pushed off the raised table 28, the cam member 52 operates the bleeder valve 152, which causes shifting of three four-way control valves (not shown) for the actuators 26, 36, and 46, respectively. Then the actuator 26 lowers the table 28 into position to receive two more rows of books of safety matches, the actuator 36 raises the carriage 38, and the actuator 46 returns the pusher 48.

As the carriage 38 is raised, the cams 108 allow the cam followers 106 and the inner grippers 82 to pivot inwardly under the influence of the springs 87, while the cam plates 110 and cam follower pins 112 retain the outer grippers 84 in their outer position, although the force of the springs 85 tending to pivot the outer grippers 84 inwardly is increased by the cams 95 and biasing arms 90. Also as the carriage is raised, the cam 124 thereon forces the cam follower 130 outwardly to pivot the arm 129, shaft 126, and arm 125 and thereby clamp the stack of inverted caddies against the frame portion 34 by the clamp 122. Further, as the inner grippers 82 pivot inwardly, the cam follower pins 97 and arms 96 are pivoted inwardly to force the opposite end portions of the bottom caddy inwardly by the surfaces 104 on the fingers 99, thereby placing the opposite end portions of the bottom caddy in proper position to be gripped. When the carriage 38 completes its upward stroke, the cam followers 112 clear the upper edges of the cam plates 110 and allow the outer grippers 84 to be snapped inwardly under the influence of the springs 85 to clamp the end portions of the bottom caddy respectively between the gripper teeth 84d and the gripper plates 82c.

The inverted caddy containing the books of safety matches lands in an essentially upright position at the bottom of the chute formed by the curved sheet member 68 and the guide rails 70, 71, and 72 and strikes the trip member 74 to operate the bleeder valve 148. Operation of the bleeder valve 148 causes shifting of a four-way control valve (not shown) for the actuator 56. The pusher 58 is then actuated by the actuator 56 to push the filled caddy along the portion 54 of the frame out of the way of the next succeeding filled caddy. The filled caddies are eventually pushed off the portion 54 of the

machine to an outlet trough or conveyor (not shown). As the pusher 58 completes its forward stroke, the cam member 60 operates the bleeder valve 154, which causes shifting of two four-way control valves (not shown) for the actuators 36 and 56, respectively. The actuator 56 then returns the pusher 58, and the actuator 36 lowers the carriage 38 to pull the bottom caddy from the stack into a position to receive the next two rows of books of matches fed upwardly by the table 28.

As the carriage 38 is lowered, the grippers 82 and 84 pull the inwardly bent opposite end portions of the gripped caddy downwardly past the support members 64 and 65, the fingers 99 and the stop members 120 being pivoted out of the way, but returning to their normal positions after the caddy has passed. Upon further lowering of the carriage 38, the cams 108 pivot the cam followers 106, inner grippers 82, and outer grippers 84 outwardly to restore the inwardly bent opposite end portions of the gripped caddy to their normal position, while the cams 95 allow the biasing arms 90 to pivot inwardly to decrease the clamping pressure between the gripper plates 82c and the gripper teeth 84d, so that the gripped caddy may later be readily stripped from the grippers by rows of books of safety matches fed upwardly by the table 28. Also, while the carriage 38 is being lowered, the cam 124 releases the clamping pressure exerted on the stack of caddies in the machine by the clamping bar 122, so that the stack of caddies may fall to place the next caddy in engagement with the support members 64 and 65, and the pivoting of the inner grippers 82 outwardly allows the arms 96 to pivot outwardly to place the surfaces 104 on the fingers 99 in proper position to force the opposite end portions of the next caddy inwardly. The cam follower pins 112 on the outer grippers 84 pivot the cam plates 110 outwardly as the carriage 38 is lowered. When the carriage 38 completes its downward stroke, the pins 112 align with the slots 114 and the plates 110 are forced inwardly of the pins 112 by the springs 118 so as to be in position to retain the outer grippers 84 in their outer position during the next upward stroke of the carriage 38.

It will be seen that I have provided a simple, inexpensive, and improved packaging machine for packing rows of books of safety matches into caddies, the caddies to be used being telescoped into one another and stacked in the machine in an inverted position, being fed one at a time in an inverted position from the bottom of the stack for the packing operation, and being inverted into an upright position after the packing operation, and the machine including vertically reciprocable gripping means for pulling the bottom caddy downwardly from the stack into a position for receiving upwardly fed books of safety matches, pressure varying means for varying the pressure with which the gripping means grip the opposite end portions of a caddy from a relatively high pressure exerted by the gripping means when the caddy is being pulled from the stack to a relatively low pressure exerted by the gripping means when the caddy is in match book receiving position so that upwardly fed books of safety matches may readily strip the caddy from the gripping means, bending means for bending the opposite end portions of the bottom caddy in the stack inwardly for gripping by the gripping means whereby one and only one caddy at a time is gripped by the gripping means even though the caddies may be telescoped into one another by varying amounts and cocked slightly from each other, and clamping means for clamping the stack of caddies to prevent upward movement of the bottom caddy into an improper position in which the bending means is inoperative to properly position the opposite end portions of the bottom caddy for gripping by the gripping means.

Various modifications may be made in the structure shown and described without departing from the spirit and scope of the invention. While the invention has been described as particularly useful for packaging books of

safety matches, other articles arranged in orderly rows may be packaged by a machine constructed in accordance with the invention.

I claim:

1. A packaging machine for feeding containers one at a time from the bottom of a stack of inverted nested containers and for packing articles therein, said machine comprising

(a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto, and

(b) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table.

2. A packaging machine for feeding containers one at a time from the bottom of a stack of inverted nested containers and for packing articles therein, said machine comprising

(a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto,

(b) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table, and

(c) horizontally reciprocable pusher means for pushing said filled inverted container off said table in said upper position thereof.

3. A packaging machine for feeding containers one at a time from the bottom of a stack of inverted nested containers and for packing articles therein, said machine comprising

(a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto,

(b) a vertically reciprocable table for horizontally receiving articles fed thereto in a lower position thereof, said table being raisable from said lower

position to push articles thereon upwardly into said inverted container held by said gripping means to fill said inverted container with said articles and to push said articles farther to strip said filled inverted container from said gripping means and dispose said filled inverted container on said table in an upper position of said table,

(c) horizontally reciprocable pusher means for pushing said filled inverted container off said table in said upper position thereof, and

(d) chute means for receiving said filled inverted container from said table and delivering said filled container in a generally upright position.

4. A packaging machine for feeding containers one at a time from the bottom of a stack of inverted nested containers and for packing articles therein, said machine comprising

(a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto,

(b) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,

(c) horizontally reciprocable first pusher means for pushing said filled inverted container off said table in said upper position thereof,

(d) chute means for receiving said filled inverted container from said table and delivering said filled container in a generally upright position,

(e) platform means for receiving said filled upright container from said chute means, and

(f) horizontally reciprocable second pusher means for pushing said filled upright container along said platform means.

5. A packaging machine for feeding containers one at a time from the bottom of a stack of inverted nested containers and for packing articles therein, said machine comprising

(a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack,

(b) a pair of spaced vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereinto, said gripping means also being movable horizontally outwardly to bend said inwardly bent opposite end portions of said inverted container back outwardly to the normal position thereof,

11

- (c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table, and
- (d) horizontally reciprocable pusher means for pushing said filled inverted container off said table in said upper position thereof.

6. A packaging machine for feeding containers one at a time from the bottom of a stack of inverted nested containers and for packing articles therein, said machine comprising

- (a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto,
- (b) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereinto,
- (c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table, and
- (d) horizontally reciprocable pusher means for pushing said filled inverted container off said table in said upper position thereof.

7. A packaging machine for feeding containers one at a time from the bottom of a stack of inverted nested containers and for packing articles therein, said machine comprising

- (a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto,
- (b) clamping means for clamping said stack of inverted nested containers to prevent movement of said bottom container into an improper position for gripping by said gripping means, said clamping means being releasable to release said stack of containers after said bottom container has been pulled downwardly therefrom,
- (c) a vertically reciprocable table for horizontally receiving articles fed thereto in a lower position there-

of, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table, and

- (d) horizontally reciprocable pusher means for pushing said filled inverted container off said table in said upper position thereof.

8. A packaging machine for feeding containers one at a time from the bottom of a stack of inverted nested containers and for packing articles therein, said machine comprising

- (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack,

- (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereinto, said gripping means also being movable horizontally outwardly to bend said inwardly bent opposite end portions of said inverted container back outwardly to the normal position thereof,

- (c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,

- (d) horizontally reciprocable pusher means for pushing said filled inverted container off said table in said upper position thereof, and

- (e) chute means for receiving said filled inverted container from said table and delivering said filled container in a generally upright position.

9. A packaging machine for feeding containers one at a time from the bottom of a stack of inverted nested containers and for packing articles therein, said machine comprising

- (a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto,

- (b) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereinto,

- (c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table.
- (d) horizontally reciprocable pusher means for pushing said filled inverted container off said table in said upper position thereof, and
- (e) chute means for receiving said filled inverted container from said table and delivering said filled container in a generally upright position.
10. A packaging machine for feeding containers one at a time from the bottom of a stack of inverted nested containers and for packing articles therein, said machine comprising
- (a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereto,
- (b) clamping means for clamping said stack of inverted nested containers to prevent movement of said bottom container into an improper position for gripping by said gripping means, said clamping means being releasable to release said stack of containers after said bottom container has been pulled downwardly therefrom,
- (c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,
- (d) horizontally reciprocable pusher means for pushing said filled inverted container off said table in said upper position thereof, and
- (e) chute means for receiving said filled inverted container from said table and delivering said filled container in a generally upright position.
11. A packaging machine for feeding containers one at a time from the bottom of a stack of inverted nested containers and for packing articles therein, said machine comprising
- (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack,
- (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereto, said gripping means also being movable horizontally outwardly to bend said inwardly bent opposite end portions of said inverted container back outwardly to the normal position thereof,
- (c) clamping means for clamping said stack of inverted nested containers to prevent movement of said bottom container into an improper position for gripping by said gripping means, said clamping means being releasable to release said stack of containers after said bottom container has been pulled downwardly therefrom,
- (d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table, and
- (e) horizontally reciprocable pusher means for pushing said filled inverted container off said table in said upper position thereof.
12. A packaging machine for feeding containers one at a time from the bottom of a stack of inverted nested containers and for packing articles therein, said machine comprising

- (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack,
- (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereto, said gripping means also being movable horizontally outwardly to bend said inwardly bent opposite end portions of said inverted container back outwardly to the normal position thereof,
- (c) clamping means for clamping said stack of inverted nested containers to prevent movement of said bottom container into an improper position for gripping by said gripping means, said clamping means being releasable to release said stack of containers after said bottom container has been pulled downwardly therefrom,
- (d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table, and
- (e) horizontally reciprocable pusher means for pushing said filled inverted container off said table in said upper position thereof.
13. A packaging machine for feeding containers one at a time from the bottom of a stack of inverted nested containers and for packing articles therein, said machine comprising
- (a) a pair of spaced, vertically reciprocable, openable and closable gripping means each including a pair of

gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereto,

- (b) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereto,
- (c) clamping means for clamping said stack of inverted nested containers to prevent movement of said bottom container into an improper position for gripping by said gripping means, said clamping means being releasable to release said stack of containers after said bottom container has been pulled downwardly therefrom,
- (d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table, and
- (e) horizontally reciprocable pusher means for pushing said filled inverted container off said table in said upper position thereof.

14. A packaging machine for feeding containers one at a time from the bottom of a stack of inverted nested containers and for packing articles therein, said machine comprising

- (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack,
- (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereto, said gripping means also being movable horizontally outwardly to bend said inwardly bent opposite end portions of said inverted container back outwardly to the normal position thereof,
- (c) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereto,
- (d) a vertically reciprocable table for horizontally receiving articles fed thereto in a lower position thereof, said table being raisable from said lower position to push articles thereon upwardly into said in-

verted container held by said gripping means to fill said inverted container with said articles and to push said articles farther to strip said filled inverted container from said gripping means and dispose said filled inverted container on said table in an upper position of said table,

- (e) horizontally reciprocable pusher means for pushing said filled inverted container off said table in said upper position thereof, and
- (f) chute means for receiving said filled inverted container from said table and delivering said filled container in a generally upright position.

15. A packaging machine for feeding containers one at a time from the bottom of a stack of inverted nested containers and for packing articles therein, said machine comprising

- (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack,
- (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereto, said gripping means also being movable horizontally outwardly to bend said inwardly bent opposite end portions of said inverted container back outwardly to the normal position thereof,
- (c) clamping means for clamping said stack of inverted nested containers to prevent movement of said bottom container into an improper position for gripping by said gripping means, said clamping means being releasable to release said stack of containers after said bottom container has been pulled downwardly therefrom,
- (d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,
- (e) horizontally reciprocable pusher means for pushing said filled inverted container off said table in said upper position thereof, and
- (f) chute means for receiving said filled inverted container from said table and delivering said filled container in a generally upright position.

16. A packaging machine for feeding containers one at a time from the bottom of a stack of inverted nested containers and for packing articles therein, said machine comprising

- (a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereto,

- (b) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereinto, 5
- (c) clamping means for clamping said stack of inverted nested containers to prevent movement of said bottom container into an improper position for gripping by said gripping means, said clamping means being releasable to release said stack of containers after said bottom container has been pulled down- 10
- wardly therefrom,
- (d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper 15
- position of said table, 20
- (e) horizontally reciprocable pusher means for pushing said filled inverted container off said table in said upper position thereof, and
- (f) chute means for receiving said filled inverted container from said table and delivering said filled container in a generally upright position. 30
17. A packaging machine for feeding containers one at a time from the bottom of a stack of inverted nested containers and for packing articles therein, said machine comprising
- (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack, 40
- (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereinto, said gripping means also being movable horizontally outwardly to bend said inwardly bent opposite end portions of said inverted container back outwardly to the normal position thereof, 45
- (c) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereinto, 60
- (d) clamping means for clamping said stack of inverted nested containers to prevent movement of said bottom container into an improper position for gripping by said gripping means, said clamping means being releasable to release said stack of containers after said bottom container has been pulled down- 70
- wardly therefrom,
- (e) a vertically reciprocable table for horizontally receiving articles fed thereto in a lower position there- 75

- of, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table, and
- (f) horizontally reciprocable pusher means for pushing said filled inverted container off said table in said upper position thereof.
18. A packaging machine for feeding containers one at a time from the bottom of a stack of inverted nested containers and for packing articles therein, said machine comprising
- (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack,
- (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereinto, said gripping means also being movable horizontally outwardly to bend said inwardly bent opposite end portions of said inverted container back outwardly to the normal position thereof,
- (c) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereinto,
- (d) clamping means for clamping said stack of inverted nested containers to prevent movement of said bottom container into an improper position for gripping by said gripping means, said clamping means being releasable to release said stack of containers after said bottom container has been pulled down- 50
- wardly therefrom,
- (e) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,
- (f) horizontally reciprocable pusher means for pushing said filled inverted container off said table in said upper position thereof, and
- (g) chute means for receiving said filled inverted container from said table and delivering said filled container in a generally upright position.
19. A packaging machine for feeding containers one at a time from the bottom of a stack of inverted nested containers and for packing articles therein, said machine comprising
- (a) a pair of spaced, horizontally reciprocable bending means respectively movable horizontally inwardly to respectively bend the opposite end portions of a bot-

- tom container in a stack of inverted nested containers inwardly and away from the opposite end portions of a next succeeding container in said stack,
- (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereto, said gripping means also being movable horizontally outwardly to bend said inwardly bent opposite end portions of said inverted container back outwardly to the normal position thereof,
- (c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,
- (d) horizontally reciprocable first pusher means for pushing said filled inverted container off said table in said upper position thereof,
- (e) chute means for receiving said filled inverted container from said table and delivering said filled container in a generally upright position,
- (f) platform means for receiving said filled upright container from said chute means, and
- (g) horizontally reciprocable second pusher means for pushing said filled upright container along said platform means.
20. A packaging machine for feeding containers one at a time from the bottom of a stack of inverted nested containers and for packing articles therein, said machine comprising
- (a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereto,
- (b) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereto,
- (c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,
- (d) horizontally reciprocable first pusher means for pushing said filled inverted container off said table in said upper position thereof,
- (e) chute means for receiving said filled inverted con-

- tainer from said table and delivering said filled container in a generally upright position,
- (f) platform means for receiving said filled upright container from said chute means, and
- (g) horizontally reciprocable second pusher means for pushing said filled upright container along said platform means.
21. A packaging machine for feeding containers one at a time from the bottom of a stack of inverted nested containers and for packing articles therein, said machine comprising
- (a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereto,
- (b) clamping means for clamping said stack of inverted nested containers to prevent movement of said bottom container into an improper position for gripping by said gripping means, said clamping means being releaseable to release said stack of containers after said bottom container has been pulled downwardly therefrom,
- (c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,
- (d) horizontally reciprocable first pusher means for pushing said filled inverted container off said table in said upper position thereof,
- (e) chute means for receiving said filled inverted container from said table and delivering said filled container in a generally upright position,
- (f) platform means for receiving said filled upright container from said chute means, and
- (g) horizontally reciprocable second pusher means for pushing said filled upright container along said platform means.
22. A packaging machine for feeding containers one at a time from the bottom of a stack of inverted nested containers and for packing articles therein, said machine comprising
- (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack,
- (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereto, said gripping means also being movable horizontally outwardly to bend said inwardly bent opposite end portions of said inverted container back outwardly to the normal position thereof,
- (c) gripping pressure varying means for varying the pressure with which said gripping means respectively

21

grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereto,

(d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table.

(e) horizontally reciprocal first pusher means for pushing said filled inverted container off said table in said upper position thereof.

(f) chute means for receiving said filled inverted container from said table and delivering said filled container in a generally upright position.

(g) platform means for receiving said filled upright container from said chute means, and

Container from said chute means, and

(h) horizontally reciprocable second pusher means for pushing said filled upright container along said platform means.

23. A packaging machine for feeding containers one at a time from the bottom of a stack of inverted nested containers and for packing articles therein, said machine comprising

(a) a pair of spaced, horizontally reciprocal bending means respectively movable horizontally inwardly to respectively bend the opposite end portions of a bottom container in a stack of inverted nested containers inwardly and away from the opposite end portions of a next succeeding container in said stack, 35

(b) a pair of spaced vertically and horizontally reciprocal, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereinto, said gripping means also being movable horizontally outwardly to bend said inwardly bent opposite end portions of said inverted container back outwardly to the normal position thereof, 40 45 50

(c) clamping means for clamping said stack of inverted nested containers to prevent movement of said bottom container into an improper position for gripping by said gripping means, said clamping means being releasable to release said stack of containers after said bottom container has been pulled downwardly therefrom

from,
(d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table.

(e) horizontally reciprocable first pusher means for pushing said filled inverted container off said table in said upper position thereof.

(f) chute means for receiving said filled inverted container from said table and delivering said filled container in a generally upright position.

22

- (g) platform means for receiving said filled upright container from said chute means, and
- (h) horizontally reciprocable second pusher means for pushing said filled upright container along said platform means.

24. A packaging machine for feeding containers one at a time from the bottom of a stack of inverted nested containers and for packing articles therein, said machine comprising

(a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto.

(b) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereto.

led upwardly thereinto,

(c) clamping means for clamping said stack of inverted nested containers to prevent movement of said bottom container into an improper position for gripping by said gripping means, said clamping means being releasable to release said stack of containers after said bottom container has been pulled downwardly therefrom,

(d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,

(e) horizontally reciprocal first pusher means for pushing said filled inverted container off said table in said upper position thereof.

(f) chute means for receiving said filled inverted container from said table and delivering said filled container in a generally upright position.

- (g) platform means for receiving said filled upright container from said chute means, and
- (h) horizontally reciprocable second pusher means for

(ii) Horizontal reciprocable second pusher means for pushing said filled upright container along said platform means.

60 23. A packaging machine for feeding containers one at a time from the bottom of a stack of inverted nested containers and for packing articles therein, said machine comprising

(a) a pair of spaced, horizontally reciprocable bending means respectively movable horizontally inwardly to respectively bend the opposite end portions of a bottom container in a stack of inverted nested con-

bottom container in a stack of inverted nested containers inwardly and away from the opposite end portions of a next succeeding container in said stack, (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said

stack and dispose said container in an inverted position for receiving articles fed upwardly thereinto, said gripping means also being movable horizontally outwardly to bend said inwardly bent opposite end portions of said inverted container back outwardly to the normal position thereof,

(c) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereinto,

(d) clamping means for clamping said stack of inverted nested containers to prevent movement of said bottom container into an improper position for gripping by said gripping means, said clamping means being releasable to release said stack of containers after said bottom container has been pulled downwardly therefrom,

(e) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table,

(f) horizontally reciprocable first pusher means for pushing said filled inverted container off said table in said upper position thereof,

(g) chute means for receiving said filled inverted container from said table and delivering said filled container in a generally upright position,

(h) platform means for receiving said filled upright container from said chute means, and

(i) horizontally reciprocable second pusher means for pushing said filled upright container along said platform means.

26. A packaging machine for feeding containers one at a time from the bottom of a stack of inverted nested containers and for packing articles therein, said machine comprising

(a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack,

(b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereinto, said gripping means also being movable horizontally outwardly to bend said inwardly bent opposite end portions of said inverted container back outwardly to the normal position thereof, and

(c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled in-

verted container on said table in an upper position of said table.

27. A packaging machine for feeding containers one at a time from the bottom of a stack of inverted nested containers and for packing articles therein, said machine comprising

(a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto,

(b) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereinto, and

(c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table.

28. A packaging machine for feeding containers one at a time from the bottom of a stack of inverted nested containers and for packing articles therein, said machine comprising

(a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto,

(b) clamping means for clamping said stack of inverted nested containers to prevent movement of said bottom container into an improper position for gripping by said gripping means, said clamping means being releasable to release said stack of containers after said bottom container has been pulled downwardly therefrom, and

(c) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table.

29. A packaging machine for feeding containers one at a time from the bottom of a stack of inverted nested containers and for packing articles therein, said machine comprising

(a) a pair of spaced, horizontally reciprocable bending means respectively movable horizontally inwardly to respectively bend the opposite end portions of a bottom container in a stack of inverted nested

- containers inwardly and away from the opposite end portions of a next succeeding container in said stack, 5
 (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereinto, said gripping means also being movable horizontally outwardly to bend said inwardly bent opposite end portions of said inverted container back outwardly 10 to the normal position thereof, 15
 (c) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereinto, and 20
 (d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table. 25
 30. A packaging machine for feeding containers one at a time from the bottom of a stack of inverted nested containers and for packing articles therein, said machine comprising
 (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack, 40
 (b) a pair of spaced vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereinto, said gripping means also being movable horizontally outwardly to bend said inwardly bent opposite end portions of said inverted container back outwardly to the normal position thereof, 45
 (c) clamping means for clamping said stack of inverted nested containers to prevent movement of said bottom container into an improper position for gripping by said gripping means, said clamping means being releasable to release said stack of containers after said bottom container has been pulled downwardly 50
 (d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table. 55

 70

- verted container on said table in an upper position of said table.
 31. A packaging machine for feeding containers one at a time from the bottom of a stack of inverted nested containers and for packing articles therein, said machine comprising
 (a) a pair of spaced, vertically reciprocable, openable and closable gripping means each including a pair of gripping portions openable to receive therebetween and closable to grip therebetween a respective one of a pair of opposite end portions of a bottom container in a stack of inverted nested containers, said gripping means being lowerable from an upper position to move said bottom container downwardly from said stack and dispose said container in an inverted position for receiving articles fed upwardly thereinto, 10
 (b) gripping pressure varying means for varying the pressure with which said gripping means respectively grip said opposite end portions of said inverted container from a relatively high pressure exerted by said gripping means when said inverted container is being pulled from said stack to a relatively low pressure exerted by said gripping means when said inverted container is in said position for receiving articles fed upwardly thereinto, 15
 (c) clamping means for clamping said stack of inverted nested containers to prevent movement of said bottom container into an improper position for gripping by said gripping means, said clamping means being releasable to release said stack of containers after said bottom container has been pulled downwardly therefrom, and 20
 (d) a vertically reciprocable table for horizontally receiving articles fed thereto in a lower position thereof, said table being raisable from said lower position to push articles thereon upwardly into said inverted container held by said gripping means to fill said inverted container with said articles and to push said articles farther to strip said filled inverted container from said gripping means and dispose said filled inverted container on said table in an upper position of said table. 25
 30
 32. A packaging machine for feeding containers one at a time from the bottom of a stack of inverted nested containers and for packing articles therein, said machine comprising
 (a) a pair of spaced, horizontally reciprocable bending means respectively movable horizontally inwardly to respectively bend the opposite end portions of a bottom container in a stack of inverted nested containers inwardly and away from the opposite end portions of a next succeeding container in said stack, 40
 (b) a pair of spaced, vertically and horizontally reciprocable, openable and closable gripping means each including a pair of gripping portions openable to receive therebetween and closable to grip therebetween a respective one of said inwardly bent opposite end portions of said bottom container, said gripping means being lowerable from an upper position to move said bottom container downwardly from said stack and dispose said container in an inverted position for receiving articles fed upwardly thereinto, said gripping means also being movable horizontally outwardly to bend said inwardly bent opposite end portions of said inverted container back outwardly to the normal position thereof, 45
 (c) gripping pressure varying means for varying the pressure with which said gripping means respectively grip said opposite end portions of said inverted container from a relatively high pressure exerted by said gripping means when said inverted container is being pulled from said stack to a relatively low pres- 50
